CROSS CONNECTOR FOR ELECTRICAL CONDUCTORS

Elmer H. Dreher, South Norwalk, Conn., assignor to Sperry Rand Corporation, a corporation of Delaware

Application March 29, 1955, Serial No. 497,698

1 Claim. (Cl. 174—87)

This invention relates broadly to electrical connectors and more particularly to an improved connector of the solderless type for use in electrically connecting crossed conductors.

In the commercial manufacture of electrical apparatus having complicated wiring circuits, such as the chassis components of electronic computers and the like where a large number of elements such as tube sockets are connected to a common conductor through short wires, it becomes necessary to electrically connect these short wires to the common conductor. The joining of a bare cross wire to an insulated wire has heretofore generally been accomplished by connecting the cross wire, sometimes referred to as a "pigtail," to a common wire through a series of soldering operations and by threading short sections of an insulation sleeve or tube, commonly referred to as "spaghetti," upon the common wire between each soldered joint at the junction of the cross and common wires. This method of joining large numbers of wires, disposed substantially at right angles to one another, is not only a slow and tedious operation but in addition is an expensive procedure.

The present invention contemplates the provision of a simple, practical and inexpensive electrical connector which has been especially designed for quickly connecting a number of discrete cross wires or pigtailed to a common wire or conductor by crimping or pressure forming the connector onto the wires in such a manner as to cause pressure separation of the insulation on one or both of the wires to effectively and positively insure and maintain an excellent electrical contact at the junction point of the wires. The term "pressure separation" as used herein is intended to mean forcefully rupturing the insulation on the wires at their junction points by crimping or externally applying pressure to the connector.

More specifically, the present invention contemplates the provision of a new and improved connector for crossed wires in which the crimped or compressed body or ferrule of the connector has opposed transverse apertures to receive the cross wire or pigtail and short finger sections or tabs adjacent such apertures to effectively hold the cross wire against "pull out" and in firm electrical contact with the connector ferrule and common conductor.

Still another object of the invention is to provide the body or ferrule portion of the connector with one or more insulation piercing prongs or barbs for further insuring good electrical contact between the body or ferrule of the connector and the common or main insulated wire.

For a better understanding of the present invention, together with other and further objects thereof, reference is made to the following description taken in connection with the accompanying drawings wherein:

Fig. 1 is a perspective view of an electrical connector embodying features of the present invention, the connector having a bared cross wire inserted through transverse openings in the connector ferrule and an insulated

2

conductor overlying the bared cross wire and lying in a trough extending longitudinally of the ferrule preparatory to crimping or pressure forming the ferrule to final shape.

Fig. 2 is a perspective view of Fig. 1 after the ferrule has been pressed or crimped to its final shape.

Fig. 3 is an enlarged transverse sectional view of the connector assembly of Fig. 2 substantially along the line 3—3 of Fig. 2.

Fig. 4 is an enlarged side elevational view of the connector assembly of Fig. 2 partly in longitudinal vertical section at the junction points of the crossed wires or electrical conductors.

Fig. 5 is a plan view of the blank used in forming the connector of Fig. 2.

Fig. 6 is a perspective view of the blank of Fig. 5 after being shaped to receive the cross wires or conductors to be electrically connected to one another.

Fig. 7 is a fragmentary plan view of an electrical device illustrating a plurality of tube sockets the wiring circuits of which include crossed wires joined by the present invention.

Fig. 8 is an isometric view similar to Fig. 6 of a modified connector.

Fig. 9 is a cross section of the connector shown in Fig. 25 after it has been crimped or pressure formed onto a pair of cross conductors or wires.

Fig. 10 is a top plan view of a strip of connectors joined end to end to illustrate their formation by conventional progressive punching and forming dies.

Fig. 11 is an enlarged cross section of the assembly shown in Fig. 1 before the connector is crimped upon the crossed wires, and

Fig. 12 is a cross section similar to Fig. 11 with the connector partially crimped upon the crossed wires and 35 before it is pressed to the final shape shown in Fig. 3.

In the embodiment of the invention shown in Figs. 1 to 6 the improved connector, for electrically connecting a pair of crossed wires or wires disposed substantially at right angles relative to one another without the use 40 of solder, is preferably stamped from sheet-metal such as beryllium, brass, annealed copper or like conductive metals of equal hardness to form a flat blank, indicated by reference numeral 10 in Fig. 5 by the use of any conventional and well known progressive punching and forming dies (not shown). The blanks 10 may be stamped separately or they may be joined end to end in a continuous strip by short lands 12 formed by punching transversely opposed notches 13 at spaced intervals along the edge of strip or roll stock sheet-metal 11 as clearly illustrated in Fig. 10.

Following the punching of the notches 13 in the sheet-metal strip 11, to define discrete rectangular blanks 10, each blank is then subsequently provided with a pair of transversely opposed apertures 14 intermediate its ends, 55 with a pair of short fingers or tabs 15 adjacent the apertures 14 and with a pair of pointed insulation piercing prongs or barbs 16 as clearly shown in Figs. 5 and 10 for reasons presently made clear.

Upon providing each blank 10 with apertures 14, tabs 60 15, and insulation piercing prongs 16, its longitudinal sides 19 are then rolled or folded upwardly in paralleled relation with respect to one another by suitable forming dies to form the blank into a substantially U-shaped cross section providing a longitudinal trough B as shown in Figs. 6 and 10. The connector A shown in Fig. 6 or strips of connectors A joined end to end by the lands 12 as shown in Fig. 10, constitutes an article of manufacture which can be sold, shipped, or stored as such until they are used for electrically connecting cross wires in 65 a manner hereinafter described.

Use of the connector A for electrically connecting a

bare cross wire or pigtail 17 to an insulated wire or conductor 18 will now be described with particular attention directed to Figs. 1 to 4 and 10 to 12. As shown in Figs. 1 and 11 the bared cross wire 17 is first inserted into and through the apertures 14 of conductor A so as to rest upon the short outwardly projecting fingers or tabs 15. The insulated conductor or wire 18 is then laid in the longitudinally extending trough B of the connector so as to overlie the cross wire 17 and insulation piercing prongs or barbs 16 as best shown in Fig. 11. With the crossed wires 17 and 18 positioned within connector A as shown in Fig. 11 external pressure is then applied to the exterior of the connector, by a suitable hand or power operated crimping or forming tool not shown, to cause the parallel wall sections 19 of the connector to be curled or rolled inwardly around the insulated conductor 18 as shown in Fig. 12. This application of external pressure upon the connector forces conductor 18 downwardly within the trough B and drives the pointed prongs 16 upwardly through the insulation 20 of conductor 18 into electrical contact with the strands of wire that form the core 21 of the insulated conductor 18. As this downward pressure is applied to the conductor 18 during the rolling or curling of the sections 19 the bare cross connector 17 is forced toward the core 21 of conductor 18, with sufficient pressure to cause pressure separation of the insulation 20 as the conductors are forced into contact with one another. At the same time the walls 19 of connector A are being bent or rolled around the exterior of insulated conductor 18, by suitable hand or power operated crimping or forming tools not shown, to drive the conductor 18 downwardly within trough B as above described, the tabs or fingers 15 are bent upwardly against the cross wire 17 as shown in Fig. 12. This upward bending of the tabs 15 contributes to the forcing of wire 17 through the insulation 20 of conductor 18 and causes the ends of the tabs to bite into conductor 17 to effectively insure good electrical contact between the conductor 17 and the connector A. When the parallel wall sections 19 are fully crimped or formed around the conductor 18, and tabs 15 have been bent into contact with the cross wire 17, as shown in the sectional view of Fig. 3, wire 17 has been driven through the insulation 20 to bring it into electrical contact with the stranded core 21 of said conductor 18.

It has been found from actual use of these electrical connectors that cross wire 17 is inclined to become slightly flattened or elliptical in cross section at the point of contact with the stranded core 21 (Fig. 4) through the external pressure applied to the connector A and tabs 15 during the crimping or forming operation of the connector onto the cross wires. An advantage of the construction just described is the extraordinarily high electrical contact that is formed between the wires 17 and 18 and the connector A without the necessity of removing any of the insulation 20 from the main conductor 18 or performing any soldering operations. Moreover the gripping action of the short tabs or fingers 15 effectively prevents "pull out" of the cross wire 17 and their closure against the wire 17, in opposition to the curling of the wall sections 19, aids in "pressure separation" of the insulation 20 to bring the cross wire 17 into good electrical contact with the stranded or solid core 21 of the common conductor 18.

In an alternative form of the invention, as shown in Figs. 8 and 9, electrical contact between the cross wire 117 and solid core 121 of conductor 118 is established entirely through pressure separation of the insulation 120 around the conductor 118. The cross wire 117 and core 121 of the main conductor 118 are forced into electrical contact with one another within the connector 110 and use of the pointed prongs or barbs 16 as previously described in connection with Figs. 5 and 6 is dispensed with.

By applying sufficient external pressure to the connector 10 of Fig. 6 or the connector 110 of Fig. 8, pressure separation of the insulation has a tendency to displace a small portion of the insulation 20 or 120 upwardly between the abutting edges of the clamping and retaining wall sections 19, as shown in Figs. 3 and 9, but this does not adversely effect the holding qualities of the connector upon the cross wires.

From the foregoing description and explanation it will now be clear that wiring circuits, such as illustrated in Fig. 7 involving insulated conductors 18 having numerous cross conductors 17 electrically connected thereto and to electrical devices such as the tube sockets S, can be quickly and economically completed by the use of the present invention without stripping any insulation from the insulated conductors 18 or soldering the cross wires 17 to the core of the insulated conductors 18.

While there is in this application specifically described two forms which the invention may assume in practice, it will be understood that these forms are shown for purposes of illustration only and that the invention may be modified and embodied in various other forms without departing from its spirit or the scope of the appended claim.

The invention claimed is:

An electrical connector of the type intended to be pressure-formed onto a pair of crossed conductors; comprising a body member having a trough-like retaining section and substantially parallel spaced wall sections formed integral with said retaining section to provide a trough for receiving one of said conductors which is insulated, and a pair of tabs punched from opposite sides of the body member and bent downwardly and outwardly therefrom to form apertures through which the other conductor may be disposed, said apertures disposed near the bottom of the body member on each side thereof and terminating below the tops of the wall sections, the other conductor being a bare conductor whereby when the wall sections are pressure-formed around the insulated conductor lying within the trough and the tabs are simultaneously curled against the bare conductor, electrical contact is established between said conductors by forcing said bare conductor through the covering of the insulated conductor.
